CARBURETOR FOR AN INTERNAL COMBUSTION ENGINE

Alfred C. Korte, Jennings, Raymond G. Hennemann, St. Louis, and Eugene L. Rapplean, Ferguson, Mo., assignors to ACF Industries, Incorporated, New York, N.Y., a corporation of New Jersey

Filed May 2, 1960, Ser. No. 60,422

Term of patent 14 years

(Cl. D77—1)

FIG. 1.

FIG. 3.

FIG. 2.

FIG. 4.

Fig. 1 is a top plan view of a carburetor, for an internal combustion engine, showing our new design.

Fig. 2 is a side elevation of same.

Figs. 3 and 4 are end elevations thereof as seen from the left and right, respectively, of Fig. 2.

We claim:

The ornamental design for a carburetor for an internal combustion engine, as shown.
